UNITED STATES PATENT OFFICE.

FRANK D. MALTBY, OF BATTLE CREEK, MICHIGAN.

PRIMING AND DECARBONIZING DEVICE FOR INTERNAL-COMBUSTION ENGINES.

1,264,953.

Specification of Letters Patent. Patented May 7, 1918.

Application filed January 2, 1917. Serial No. 140,136.

To all whom it may concern:

Be it known that I, FRANK D. MALTBY, a citizen of the United States, residing at Battle Creek, county of Calhoun, State of Michigan, have invented certain new and useful Improvements in Priming and Decarbonizing Devices for Internal-Combustion Engines, of which the following is a specification.

10 This invention relates to improvements in priming and decarbonizing devices for internal combustion engines.

The main objects of this invention are:

First, to provide an improved priming and decarbonizing device for internal combustion engines which may be quickly and easily operated to prime the engine or to adjust the device to conduct water to the engine for decarbonizing purposes.

20 Second, to provide an improved device of the class described which may be applied to motor vehicle engines, so as to be operated from the dash or from the front of the vehicle.

25 Third, to provide an improved device of the class described which does not interfere with the normal operation of the carbureter, but which, if desired, may be adjusted to supplement the carbureter in its normal operation.

Fourth, to provide an improved device having these advantages which is comparatively simple in its parts and not likely to get out of repair or to become inoperative.

35 Further objects, and objects relating to structural details, will definitely appear from the detailed description to follow.

I accomplish the objects of my invention by the devices and means described in the 40 following specification. The invention is clearly defined and pointed out in the claims.

A structure which is a preferred embodiment of my invention is clearly illustrated in the accompanying drawing, forming a 45 part of this specification, in which:

Figure I is a detail side elevation of an adaptation of a structure embodying the features of my invention, it being shown in operative relation to a carbureter, manifold, 50 and radiator.

Fig. II is an enlarged detail view, partially in longitudinal section, on a line corresponding to line 2—2 of Figs. I and III.

55 Fig. III is an enlarged detail section on a line corresponding to line 3—3 of Figs. I, II and V.

Fig. IV is an enlarged detail section through the air and water valve showing structural details thereof.

Fig. V is a detail section on a line corresponding to line 5—5 of Figs. II and III, showing further details of the air and water valve and its connection to the manifold.

Fig. VI is a detail section on a line corresponding to line 6—6 of Figs. I, V and VII, showing the arrangement of the return spring for the air and water valve.

Fig. VII is an enlarged detail of the combined air and water valve.

Fig. VIII is an elevation view of the air and water valve hand piece and indicator.

Fig. IX is a detail section on a line corresponding to line 9—9 of Fig. I, showing details of the means for operating the plunger when it is used as a regulating valve.

Fig. X is a detail side elevation of an adaptation of my improvements with the primer actuating rod arranged through the radiator of a motor vehicle.

In the drawing similar reference characters refer to similar parts throughout the several views, and the sectional views are taken looking in the direction of the little arrows at the ends of the section lines.

Referring to the drawing, 1 designates the manifold of an internal combustion engine, and 2 the carbureter. The manifold illustrated is that of the Ford automobile. 3 represents the radiator, and 4 the dash or front of the vehicle.

I provide a priming pump cylinder 5 and a coacting plunger 6, the plunger being provided with a suitable packing 7 and a rod 8 which projects from the cap 9 of the cylinder to be operated at the instrument board or dash, as shown in the adaptation of Fig. I, or at the front of the machine, as shown in Fig. X, in which the rod 8 is arranged through the radiator in convenient position so that the primer may be actuated and the engine cranked in quick succession.

The adaptation shown in Fig. I is desirable where the vehicle is provided with a self-starter or other cranking means. To permit these different adaptations the cylinder is provided, with a passage arm 11 threaded into the manifold at its central or branching point, the arm constituting a pivot permitting the adjustment of the cylinder to different positions, as indicated.

110 The arm 11 is provided with an atomizing and spraying nozzle 12 which projects cen-

trally into the manifold cylinder. The delivery passage is provided with a return check 13 held upon its seat by the spring 14, the outer end of the spring being seated 5 against the nozzle. The plunger is held normally in its initial position by means of the coiled spring 15 which is arranged on the plunger rod 8, as shown in Fig. II. The inner end of the plunger is beveled at 16 10 so that it may be adjusted to constitute a regulating valve for the delivery port 17.

The inlet valve 18 of the cylinder is seated in the tubular valve seat member 19, which is arranged in the inner end of the cylinder 15 and shouldered at 20, see Fig. III. This valve seat member is clamped in place by the coupling 21. The fuel supply pipe 22 leads from this coupling 21 to the fuel supply 23 of the carburetor, see Fig. I. The 20 valve 18 is held on its seat by the plunger when the plunger is in its initial position. A coiled spring 24 on the stem 25 of the inlet valve tends to close this valve. These parts are the same, or substantially the same, 25 as those illustrated and described in my companion application, Serial Number 139,887, filed Dec. 30, 1916, in which I make claims thereto.

The passage arm 11 contains a second 30 passage 26 delivering into the manifold and terminating without the manifold in an annular groove 27 about the arm.

I provide an air and water inlet valve comprising a casing 28 having a sleeve or 35 bracket 29 mounted upon the passage arm to embrace the groove 27. This sleeve is rotatable upon the arm to permit the adjustment of the valve either to the position shown in the adaptation of Fig. I or that 40 of Fig. X, or other desired positions.

The valve casing 28 is provided with a delivery port 30 registering with the groove 27 and with an air inlet port 31 and a water inlet port 32. The water inlet port 32 is 45 connected by the conduit 33 with the radiator 3 or other source of water supply so as to receive water therefrom.

The valve 34 is provided with a port 35 adapted to connect either ports 31 or 32 with 50 the delivery port 30, so that either air or water may be delivered to the manifold or when the valve is closed both ports are cut off.

The valve 34 is of the rotary tapered plug 55 type and is held in its seat by the spring 36. The stem 37 of this valve is arranged through the dash and provided with a finger piece 38 and an index 39, an index plate 40 being mounted in coacting relation to this 60 index finger and provided with suitable indicia indicating the air and water delivering positions of the valve.

As the embodiment illustrated is only designed to deliver water when it is desired 65 to decarbonize the cylinders the valve stem

is provided with a spring 41 mounted on the valve stem 37 and connected thereto at one end by means of the collar 42 and set screw 43. The inner end of the spring terminates in an arm 44 adapted to engage 70 with the shoulder or stop 45 on the valve casing when the valve is turned to connect the water port 32, the spring being thereby put under tension, so that as soon as the stem is released the valve is actuated to cut off the 75 water.

The applicant has found that by occasionally supplying water for short periods the cylinders may be very effectively decarbonized.

It is desirable, under certain conditions, 80 that an additional or supplemental supply of air be delivered to the manifold.

By adjusting the valve 34 to connect the air inlet port 31 a supplemental supply of 85 air is delivered to the manifold. The spring is inoperative when the valve is adjusted to this position so that it remains in its adjusted position until manually shifted.

The plunger 8 is provided with a suitable 90 finger piece 46 which is, in the adaptation of Fig. I, arranged through the dash in convenient position for manipulation. When the plunger is used as a regulating valve for the discharge port 17 I operate the same by 95 means of a lever 47 which is forked at 48 to engage the collar 49 on the plunger rod, the lever being pivoted at 50 in convenient position to be operated by the foot of the driver. A stop screw 51 is provided to limit 100 the movement of the plunger.

In the event that the carburetor becomes 105 inoperative or an additional supply of fuel is desired the plunger may be retracted and the fuel is then drawn through the primer into the manifold, and, owing to the position of the nozzle 12, it is effectively atomized by the incoming air.

My improved priming and decarbonizing device is simple in structure and is easily installed or applied to engines as commonly 110 constructed and may be adapted for manipulation from the front of the vehicle as is desirable where the engine is to be cranked by hand or operated from the dash or instrument board where the vehicle is provided with a self-starter or cranking means.

The device is mounted so that the nozzle is central in the manifold, thus providing a uniform distribution to the several cylinders.

I have illustrated and described my improvements in the form in which I have embodied the same in use. I have not attempted to illustrate or describe various modifications which might be desirable for adapting 125 my improvements to meet different conditions and the various forms of manifolds which are in use, as I believe the disclosure made will enable those skilled in the art to which my invention relates to embody or 130

adapt the same as conditions may require. I desire, however, to be understood as claiming my invention in the form illustrated as well as broadly within the scope of the appended claims.

Having thus described my invention, what I claim as new and desire to secure by Letters Patent, is:

1. The combination with the manifold of an internal combustion engine, of a priming pump cylinder provided with a laterally directed delivery passage arm threaded into said manifold and constituting a pivot permitting the adjustment of the cylinder to different positions, said arm being provided with a fuel delivery passage and with an air and water delivery passage terminating without the manifold in a circumferential groove, a check valve for said fuel passage, 15 a cylinder inlet valve disposed at the inner end of said cylinder, a plunger adapted when in its initial position to close said fuel passage and to retain said inlet valve on its seat, said plunger being also adapted for adjustment to constitute a regulating valve for said fuel passage, a return spring for said plunger, a combined air and water inlet valve casing provided with a sleeve rotatably mounted on said arm to embrace said passage groove thereof and with a delivery port communicating with said groove, and with air and water inlet ports, the water inlet port being connected with a source of water supply, a rotary valve adjustable to 30 connect said water or said air inlet ports with the said delivery ports or to close such ports, and a spring arranged so that it is placed under tension when said valve is adjusted to connect said water port whereby it tends to close such port when the valve is released, said spring being inoperative to close the valve when it is adjusted to air delivery position.
2. The combination with the manifold of an internal combustion engine, of a priming pump provided with a laterally directed delivery passage arm threaded into said manifold and constituting a pivot permitting the adjustment of the cylinder of the pump to different positions, said arm being provided with a fuel delivery passage and with an air and water delivery passage terminating without the manifold in a circumferential groove, a combined air and water inlet valve casing provided with a sleeve rotatably mounted on said arm to embrace said passage groove thereof and with a delivery port communicating with said groove, and with air and water inlet ports, the water inlet port being connected with a source of water supply, a rotary valve adjustable to connect said water or said air inlet ports with the said delivery ports or to close such ports.

valve is adjusted to connect said water port whereby it tends to close such port when the valve is released, said spring being inoperative to close the valve when it is adjusted to air delivery position.

3. The combination with the manifold of an internal combustion engine, of a priming pump cylinder provided with a laterally directed delivery passage arm threaded into said manifold and constituting a pivot permitting the adjustment of the cylinder to different positions, said arm being provided with a fuel delivery passage and with an air and water delivery passage terminating without the manifold in a circumferential groove, a check valve for said fuel passage, a cylinder inlet valve disposed at the inner end of said cylinder, a plunger adapted when in its initial position to close said fuel passage and to retain said inlet valve on its seat, said plunger being also adapted for adjustment to constitute a regulating valve for said fuel passage, a return spring for said plunger, a combined air and water inlet valve casing provided with a sleeve rotatably mounted on said arm to embrace said passage groove thereof and with a delivery port communicating with said groove, and with air and water inlet ports, the water inlet port being connected with a source of water supply, a rotary valve adjustable to connect said water or said air inlet ports with the said delivery ports or to close such ports.

4. The combination with the manifold of an internal combustion engine, of a priming pump provided with a laterally directed delivery passage arm threaded into said manifold and constituting a pivot permitting the adjustment of the cylinder to different positions, said arm being provided with a fuel delivery passage and with an air and water delivery passage terminating without the manifold in a circumferential groove, a combined air and water inlet valve casing provided with a sleeve rotatably mounted on said arm to embrace said passage groove thereof, and with a delivery port communicating with said groove, and with air and water inlet ports, the water inlet port being connected with a source of water supply, and a rotary valve adjustable to connect said water or said air inlet ports with the said delivery ports or to close such ports.

5. The combination with the manifold of an internal combustion engine, of a priming pump provided with a delivery passage arm adjustably mounted on said manifold, said arm being provided with a fuel delivery passage and with an air and water delivery passage terminating without the manifold in a transverse groove, a combined air and water inlet valve casing adjustably mounted on said arm to embrace said passage groove thereof and provided with a delivery port

- communicating with said groove and with air and water inlet ports, the water inlet port being connected with a source of water supply, a valve adjustable to connect said 5 water or said air inlet ports with the said delivery port or to close said ports, and a spring arranged so that it is placed under tension when said valve is adjusted to connect said water port whereby it tends to close 10 such port when the valve is released, said spring being inoperative to close the valve when it is adjusted to air delivery position.
6. The combination with the manifold of an internal combustion engine, of a priming 15 pump provided with a delivery passage arm adjustably mounted on said manifold, said arm being provided with a fuel delivery passage and with an air and water delivery passage terminating without the manifold 20 in a transverse groove, a combined air and water inlet valve casing adjustably mounted on said arm to embrace said passage groove thereof and provided with a delivery port communicating with said groove 25 and with air and water inlet ports, the water inlet port being connected with a source of water supply, and a valve adjustable to connect said water or said air inlet ports with the said delivery port or to close said ports.
- 30 7. The combination with the manifold of an internal combustion engine, of a priming pump cylinder provided with a laterally directed delivery passage arm threaded into said manifold and constituting a pivot permitting the adjustment of the cylinder to different positions, said arm being provided with a fuel delivery passage and with a second passage terminating without the manifold in a circumferential groove, a 35 check valve for said fuel passage, a cylinder inlet valve disposed at the inner end of said cylinder, a plunger adapted when in its initial position to close said fuel passage and to retain said inlet valve on its seat, said 40 plunger being also adapted for adjustment to constitute a regulating valve for said fuel passage, a return spring for said plunger, and a second valve provided with a sleeve rotatably mounted on said arm to embrace 45 said passage groove thereof and with a delivery port communicating with said groove.
8. The combination with the manifold of an internal combustion engine, of a priming pump provided with a delivery passage arm 50 threaded into said manifold and constituting a pivot permitting the adjustment of the cylinder to different positions, said arm being provided with a fuel delivery passage and with a second passage terminating without the manifold in a circumferential groove, and a valve provided with a sleeve 55 rotatably mounted on said arm to embrace said passage groove thereof and with a delivery port communicating with said groove.
9. The combination with the manifold of an internal combustion engine, of a priming pump having a delivery passage arm provided with a fuel delivery passage and with an air and water delivery passage, a combined air and water inlet valve provided with a delivery 60 port communicating with said air and water delivery passage and with said air and water inlet ports, a valve adapted to connect said water or said air inlet ports with the said delivery port or to close 65 said ports, and a spring arranged so that it is placed under tension when said valve is adjusted to connect said water port whereby it tends to close such port when the valve is released, said spring being inoperative to so close the valve when it is adjusted to air delivery position.
10. The combination with the manifold of an internal combustion engine, of a priming pump cylinder provided with a delivery 70 passage arm having a pair of passages therein, one of said passages being a fuel passage, a valve for the other passage comprising a valve casing adjustably mounted on said arm so that it may be adjusted to different positions, a check valve for said fuel passage, and a plunger adapted when in its initial position to close said fuel passage, said plunger being also adapted for adjustment to constitute a regulating valve for 75 said fuel passage.
11. The combination with the manifold of an internal combustion engine, of a priming pump cylinder provided with a delivery 80 passage arm having a pair of passages therein, one of said passages being a fuel passage, a valve for the other passage comprising a valve casing adjustably mounted on said arm so that it may be adjusted to different positions, a check valve for said fuel passage, and a plunger adapted when in its initial position to close said fuel passage.
12. The combination with a manifold of an internal combustion engine, of a priming 85 pump having a delivery passage arm provided with a pair of passages, said arm being adjustably mounted on said manifold so that said pump may be adjusted to different positions, one of said passages being a fuel 90 passage, and a valve for the other passage comprising a valve casing adjustably mounted on said arm.
13. The combination with the manifold of an internal combustion engine, a priming 95 pump having a delivery passage arm provided with a fuel delivery passage and with an air and water delivery passage communicating with said manifold through said arm, said manifold having a single opening in 100 which said arm is disposed, a combined air and water inlet valve casing mounted on said arm and provided with a delivery 105

port communicating with said air and water delivery passage thereof and with the air and water inlet port, and a valve adapted to connect said water and said air inlet ports with said delivery port or to close said ports.

14. The combination with a manifold of an internal combustion engine, of a priming pump having a delivery passage arm provided with a pair of passages communicating with said manifold through said arm, said manifold having a single opening in which said arm is disposed, one of said passages being a fuel passage, and a valve for the other passage comprising a valve casing adjustably mounted on said arm so that it may be adjusted to different positions, said valve casing having a delivery passage communicating in the different adjustments of said casing with said second passage of said arm.

15. The combination with a manifold, of an internal combustion engine, of a priming pump having a delivery passage arm provided with a pair of passages communicating with said manifold through said arm, said manifold having a single opening for said passage arm, one of said passages being a fuel passage, and a valve for controlling the

other passage comprising a valve casing adjustably mounted on said arm.

16. The combination with a manifold, of an internal combustion engine, of a priming pump having a delivery passage arm provided with a pair of passages communicating with said manifold through said arm, said manifold having a single opening for said passage arm, one of said passages being a fuel passage, and the other being adapted to admit air, and a valve for controlling the second passage.

17. The combination with a manifold, of an internal combustion engine, of a priming pump having a delivery passage arm provided with a pair of passages communicating with said manifold through said arm, said manifold having a single opening for said passage arm, one of said passages being a fuel passage, and the other being adapted to admit water, and a valve for controlling the second passage.

In witness whereof, I have hereunto set my hand and seal in the presence of two witnesses.
